UNITED STATES PATENT OFFICE.

ALLAN L. McGREGOR, OF CHICAGO, ILLINOIS.

AUTOMOBILE-BUFFER.

1,103,981.

Specification of Letters Patent. Patented July 21, 1914.

Application filed May 5, 1911. Serial No. 625,342.

To all whom it may concern:

Be it known that I, ALLAN L. McGREGOR, a citizen of the United States, residing at Chicago, in the county of Cook and State 5 of Illinois, have invented certain new and useful Improvements in Automobile-Buffers, of which the following is a specification.

This invention relates to buffers or bumpers used on automobiles, and has reference 10 more particularly to that type of buffer now quite extensively used, wherein a horizontally disposed buffer-bar is yieldably mounted upon and in advance of the forwardly projecting ends of the machine frame.

15 The leading object of the invention is to provide a simple, inexpensive, and efficient device for the purpose stated, capable of ready application to the machine frame without the necessity of drilling or cutting 20 the latter to accommodate the attaching means, and wherein the buffer-bar itself shall be capable of vertical adjustment, within certain limits, relatively to the forward end of the machine frame.

25 A minor object of the invention is to provide a novel and inexpensive form of buffer-bar itself, and one which may easily be made adjustable to differing widths of machine frame.

30 My invention, its structural features, mode of use, and practical advantages, will all be apparent from a consideration of the following description, taken in connection with the accompanying drawing, which illustrates 35 one practical form in which the invention may be dressed, and in which—

Figure 1 is a top plan view of my improved automobile buffer, showing the same as mounted on the forward end of the vehicle 40 frame, and Fig. 2 is an enlarged view mainly in side elevation, but with the buffer-bar appearing in cross section.

Referring to the drawing, 10 designates the forwardly and downwardly curved end 45 portions of the usual side bars of the machine frame, to the forward ends of which are pivoted, by hinge-bolts 11, the usual semi-elliptic springs 12.

13 designates the buffer-bar. In the preferred form of this bar it is made with an inwardly disposed flat horizontal web, the bar herein shown being of T-bar form with its central web 13' disposed inwardly or toward the front end of the vehicle. The web 50 13' is provided with two series of bolt-

holes 14 to facilitate the attachment thereto of a pair of buffer-bar carrying arms 15 which, as herein shown, have forked forward ends or heads 15' that straddle the web 13' and are apertured to receive fastening 60 bolts 16 that pass through one of the holes 14 of the buffer-bar near the opposite ends of the latter.

The carrying arms 15 are guided and supported in a pair of hollow bars 17, which latter are rigidly secured at their inner ends to a pair of clamps mounted on the side bars 10, the bars 17 projecting in a substantially horizontal direction forwardly of said clamps, and being secured to the latter with 70 capacity for angular adjustment, so as to vary, within certain limits, the height of the bar 13 relatively to the forward end of the vehicle frame.

The clamps herein shown comprise a pair 75 of upper and lower clamp-plates 18 and 19 engaging respectively, the upper and lower sides of the side bar 10, and apertured at their four corners to receive clamp-bolts 20. On the upper clamp-bar 18 is an integral up- 80 standing lug or ear 21 formed on one side with a ratchet face 21' which cooperates with a similar ratchet face 17' formed on the inner end of the guiding and supporting bar 17. The said ratchet faces are drawn together by a screw-bolt 22, whereby the bars 17 are rigidly held in any angularly adjusted position.

As above stated, the carrying arms 15 have a sliding engagement within the forward end portions of the guiding and supporting bars 17, and are encircled by cushioning springs 23 that abut at their inner ends against the forward ends of the bars 17, and at their forward ends abut against 95 the forked heads 15' of the arms 15, thereby normally maintaining the buffer-bar and its carrying arms projected forwardly of the supporting and guiding members 17. To confine the arms 15 against displacement 100 under the thrust of the springs, the inner ends of the arms 15 are provided with cotter-pins 24 that abut against the inner ends of the forward sleeve portions of the bars 17 formed by skeletonizing said bars some 105 distance back of their forward ends.

From the foregoing it will be seen that my improved buffer is of simple and economical construction, and is capable of a considerable range of adjustment both ver- 110

tically and horizontally of the forward end of the machine frame, the vertical adjustment being effected by a relative turning of the coöperating ratchet members 21' and 17', and the horizontal adjustment being effected by shifting the clamps longitudinally of the side frame bars 10. At the same time the use of a ribbed or webbed form of buffer-bar facilitates the attachment of the latter to the carrying arms, and especially the adjustment of such carrying arms to varying widths of machine frame.

It will be evident to those skilled in the art that the particular forms and relative arrangements of the parts described might be varied in detail without involving any departure from the principle of the invention or sacrificing any of the advantages thereof. Hence, I do not limit the invention 20 to the particular structure herein disclosed.

except to the extent clearly indicated in specific claim.

I claim—

An automobile buffer comprising, in combination, a buffer-bar, clamps adapted to be secured to the side bars of the vehicle frame, rearwardly extending buffer-bar carrying arms, hollow bars in which said carrying arms are slidably mounted, coöperating ratchet plates on said clamps and the inner ends of said hollow bars, respectively, a tightening bolt extending through said ratchet plates, and cushioning springs surrounding said arms and abutting against the forward ends of said hollow bars, substantially as described.

ALLAN L. McGREGOR.
